CLAIM

The ornamental design for a tri-fold electronic greeting card, as shown and described.

DESCRIPTION

FIG. 1 is a perspective view of a first embodiment of the tri-fold electronic greeting card, with a USB port in a first position.

FIG. 2 is a front view of the tri-fold electronic greeting card of FIG. 1.

FIG. 3 is a left side view of the tri-fold electronic greeting card of FIG. 1.

FIG. 4 is a right side view of the tri-fold electronic greeting card of FIG. 1.

FIG. 5 is a top view of the tri-fold electronic greeting card of FIG. 1.

FIG. 6 is a bottom view of the tri-fold electronic greeting card of FIG. 1.

FIG. 7 is a perspective view of the tri-fold electronic greeting card of FIG. 1, with the USB port in a second position.

FIG. 8 is a perspective view of the tri-fold electronic greeting card of FIG. 1, in a fully extended upright position.

FIG. 9 is a perspective view of a second embodiment of the tri-fold electronic greeting card.

FIG. 10 is a front view of the tri-fold electronic greeting card of FIG. 9.

FIG. 11 is a left side view of the tri-fold electronic greeting card of FIG. 9.

FIG. 12 is a right side view of the tri-fold electronic greeting card of FIG. 9.

FIG. 13 is a top view of the tri-fold electronic greeting card of FIG. 9, identical to the bottom view thereof; and,

FIG. 14 is a perspective view of the tri-fold electronic greeting card of FIG. 9 in a fully extended upright position.
